UNITED STATES PATENT OFFICE

FRANK KASPAR, OF CHICAGO, ILLINOIS, ASSIGNOR TO S. KARPEN & BROS., OF CHICAGO, ILLINOIS, A CORPORATION OF WEST VIRGINIA

CUSHION CONSTRUCTION

Application filed May 14, 1926. Serial No. 109,078.

This invention relates particularly to cushions adapted for automobile purposes, for sleeping car purposes, or the like.

The primary object is to provide an improved cushion of staunch construction which possesses important advantages from the standpoints of comfort and durability.

A modification of the present invention is disclosed in my pending application, Serial No. 109,079, filed of even date herewith.

The invention is illustrated in its preferred embodiment in the accompanying drawings in which—

Figure 1 represents a plan view, partly in section, of a cushion embodying the invention; Fig. 2 a broken vertical sectional view of the same, the section being taken as indicated at line 2 of Fig. 1; Fig. 3 a broken inner face view of the bottom of the structure, showing an air-valve applied thereto; Fig. 4 a sectional view similar to that shown in Fig. 2, illustrating a slight modification; and Fig. 5 a similar sectional view, illustrating another modification.

In the construction illustrated in Figs. 1-3, the cushion comprises a rectangular base frame A which supports a bottom A'; a marginal row of upholstery springs B supported on the frame A and connected at their upper ends with a marginal rod B'; an inner body of upholstery springs C comprising a lower nest of springs C' and an upper nest of springs C², the upper ends of the marginal row of the upper tier of inner springs being connected with a marginal rod C³; a filling of suitable stuffing or wadding material D, such as hair, moss or cotton disposed above the springs; and a covering E which may comprise a ply of burlap 1 and a finish fabric 2.

The springs B of the outer marginal row preferably are encased in individual pockets, or coverings, of fabric 3; and the springs are united at their upper ends by ties or stitches 3^a. The springs B are connected also with the marginal rod B', as by means of ties or stitches 3^b.

Preferably the inner or main body of springs C comprises the upper and lower tiers C² and C' respectively, the lower tier

being supported on the bottom A' which may be regarded as a part of the base of the structure, and the upper tier being supported directly upon the lower tier, and rising a substantial distance above the upper ends of the outer marginal row of springs B. Preferably, also, the springs of the lower tier C' are heavier and stiffer than the springs of the upper tier C². The springs of the lower tier are encased in individual fabric casings, or pockets, 4, and the springs of the upper tier are encased in individual fabric coverings 5. The upper ends of the marginal springs of the lower tier C' are connected with a marginal rod C⁴. Ties 6 serve to connect the marginal rows of the inner tiers of springs with the marginal rods C³ and C⁴. The springs of the inner main body are connected together by means of ties 7.

The base of the structure comprises the rectangular frame and the bottom A'. The bottom A' may be of any suitable construction. In the illustration given, it is composed of strong webbing 8 which is secured to the upper portion of the rectangular frame A.

A fabric 9, which may be of burlap, is stretched over the springs of the lower tier C', and is provided with skirt portions 9^a. A fabric 10 is stretched over the upper tier of springs C² and is provided with skirt portions 10^a. The skirt portions 9^a and 10^a of these fabrics are tacked to the frame A, as indicated at 11.

The fabrics 9 and 10 may be of burlap, or they may be of a suitable fabric of substantially air-tight character, so that air will not readily escape through the fabric. If desired, more than one ply of fabric may be used as a covering for each of the inner tiers of springs.

The bottom A' may be composed of a strong, heavy fabric, or of several plies of fabric, and may be substantially air-tight. It is preferred to provide the bottom with perforations 12 covered on the inside by upwardly opening valves 13 (one shown). Such valves are adapted to open upwardly to admit air within the cushion structure when the cushion expands, and are adapted to retard the expulsion of air when the cushion is

compressed. Thus, the cushion partakes of the nature of a pneumatic cushion.

The outer marginal row of springs B preferably is considerably stronger than the springs of the inner upper tier C².

5 The plies of fabric comprising the covering E are stretched over the filling material B and the springs. The skirt portions 1^a and 2^a of these fabrics are tacked to the bottom of the frame A, as indicated at 14.

10 The upper end portions of the outer marginal row of springs B are connected, by ties 15, with the adjacent portions of the springs of the upper tier C². These connections are some distance below the upper ends of the

15 springs C². While the outer marginal row of springs B is thus anchored to the inner main body of springs, there is a certain independent action of the main body of springs when the cushion is occupied. This is due

20 partly to the greater length of the main body of springs (considering the upper and lower tiers as a unit), partly to the manner in which the inner main body of springs is connected

25 with the outer marginal row of springs, and partly to the fact that the upper tier of the inner main body of springs is more yielding than the outer marginal row of springs.

Also, there is a certain advantage gained 30 by having the upper tier of the main body of springs lighter than the lower tier. Thus the upper tier will yield readily to the person, while the lower tier will resist undue compression and tend to prevent undue sagging of the cushion.

Otherwise stated, the inner main body of springs, considered as a whole, will yield readily and conform to the person, while the outer row of springs will offer more resistance and tend to give a certain desired firmness of support to the limbs near the knees. This action will occur without inconvenience to the person seated on the cushion, owing to the fact that the marginal row of the inner main body of springs will yield rather readily when the person is seated. Moreover, the outer marginal row of springs tends to prevent sagging of the cushion at its peripheral portion, which is a very desirable feature.

35 Again, the use of the marginal rods, or heavy wires, spaced in the manner illustrated, provides greater strength for the cushion as a whole, without sacrificing desired flexibility and resilience.

40 In the modification shown in my co-pending application mentioned above, the springs of the inner main body consist of a single tier of sufficient length to rise from the base to a substantial distance above the outer marginal row of springs.

45 In the modification shown in Fig. 4 of the accompanying drawings, the construction corresponds with the construction shown in Fig. 2, except that the bottom, designated A², is composed of cross-strips of strong web-

bing which are tacked to the frame A; and the lower tier of springs, designated C⁵, is considerably heavier and stronger than the lower springs of the first described construction, and is not encased in individual pockets. The other elements corresponding with the construction shown in Fig. 2 are designated by corresponding reference characters.

70 In the modification shown in Fig. 5, the construction corresponds with the construction shown in Fig. 2, except that the bottom forming a portion of the base and designated A³ is formed of sheet metal. This sheet metal member is provided with an upturned marginal flange 16 which fits within the frame A and is equipped with outturned lugs 10^a which are secured to the upper surface of the frame A. In this case, the lower tier of springs C⁵ is supported upon the depressed bottom A³. The other elements in the construction shown in Fig. 5 correspond with the construction shown in Fig. 2, and are designated by corresponding reference characters.

75 In all of the constructions described, the central body of springs presents a readily yielding upper portion. This feature is also present in the construction described in my co-pending application mentioned above.

80 On the other hand, where the central body of springs is composed of two tiers, greater staunchness of construction is secured by reason of the use of an intermediately located marginal rod C⁴; and an even more staunch and durable cushion is provided, but with some sacrifice in softness, where the lower tier of the central body of springs is of relatively stiff springs.

85 The improved cushion is a self-contained structure which may be placed upon any suitable support. The improved cushion may be made of necessary length and of the right proportions to serve as a seat cushion or as a back cushion in a sleeping car berth, where the advantages noted are highly desirable.

90 The foregoing detailed description has been given for clearness of understanding only, and no unnecessary limitations should be understood therefrom, but the appended claims should be construed as broadly as permissible in view of the prior art.

95 What I regard as new and desire to secure by Letters Patent is:

1. A cushion comprising a base, an outer marginal row of relatively stiff upholstery 100 springs mounted on said base, an inner main body of upholstery springs mounted directly on said base and extending substantially above said outer marginal row of springs, the upper portion of the inner main body of 105 springs being relatively yielding and the lower portion being relatively stiff, individual fabric casings enclosing individual 110 springs of the groups mentioned, a marginal rod secured to the upper end portions of the 115

- outer marginal row of springs, a marginal rod secured to the upper portion of the main body of springs, connections between the upper portion of the outer row of springs and the adjacent intermediate portions of the inner main body of springs, stuffing material above said springs, and a flexible covering enclosing the stuffing material and springs and secured to said base.
- 5
- 10 2. A cushion comprising a base; a main body of upholstery springs comprising a lower tier of relatively strong springs mounted on said base, a marginal rod connected with the upper ends of the marginal row of said springs, an upper tier of relatively light springs mounted on said lower tier, coverings enclosing the individual springs of the upper tier, and a marginal rod connected with the upper portion of the marginal row of springs
- 15
- 20 of said upper tier; a fabric stretched over said main body of springs and secured to said base; an outer row of relatively stiff upholstery springs mounted on said base and extending above the plane between said tiers
- 25 of springs and terminating below the plane of the upper ends of said upper tier, fabrics covering the individual springs of said outer row, ties connecting the upper ends of the springs of said outer row with intermediate
- 30 portions of the adjacent springs of said upper tier; stuffing material above said springs; and a flexible covering enclosing the stuffing material and springs and secured to said base.
